UNITED STATES PATENT OFFICE

PETER S. HARDY, OF STRATFORD, CONNECTICUT, ASSIGNOR TO HEALTH DEVELOPING APPARATUS COMPANY, INC., OF NEW YORK, N. Y., A CORPORATION OF DELAWARE

DESIGN FOR A REAR FRAME MEMBER FOR ROWING MACHINES

Application filed March 8, 1932. Serial No. 43,127. Term of patent 7 years.

To all whom it may concern:

Be it known that I, PETER S. HARDY, a citizen of the United States, residing at Stratford, county of Fairfield, State of Connecticut, have invented a new, original, and ornamental Design for a Rear Frame Member for Rowing Machines, of which the following is a specification, reference being had to the accompanying drawing, forming part thereof.

Fig. 1 is a perspective view of the rear frame member for a rowing machine showing my new design.

Fig. 2 is a plan view.

Fig. 3 is a front elevation.

I claim:

The ornamental design for a rear frame member for rowing machines, as shown.

PETER S. HARDY.
